UNITED STATES PATENT OFFICE.

CLAUDE A. P. TURNER, OF MINNEAPOLIS, MINNESOTA.

STEEL-SKELETON CONCRETE CONSTRUCTION.

1,003,384.

Specification of Letters Patent. Patented Sept. 12, 1911.

Continuation of application Serial No. 242,431, filed January 23, 1905. This application filed June 11, 1907.
Serial No. 378,444.

To all whom it may concern:

Be it known that I, CLAUDE A. P. TURNER, of Minneapolis, in the county of Hennepin and State of Minnesota, have invented 5 certain new and useful Improvements in Steel-Skeleton Concrete Construction, of which the following is a specification.

My invention relates to buildings or structures erected of reinforced concrete, and the 10 object of my invention is to provide a column and slab or floor construction, requiring a minimum of concrete and reinforcement, but having all necessary strength, to the end that the cost of erection, both in 15 respect to material and time required, may be substantially reduced and to secure certain important advantages which result from the structure which may be produced in accordance with my invention.

20 My invention is clearly illustrated in the accompanying drawings, fully described in the following paragraphs of this specification, and particularly referred to in the subjoined claims.

25 In the drawing, Figure 1 is a fragmentary side elevation of a reinforced column and floor slab, constructed in accordance with my invention, the reinforcement being shown by dotted lines; Fig. 2 a detail thereof, being a cross section of Fig. 1 taken on the line 2-2; Fig. 3 a top or plan view of the column reinforcement, and portions of the floor slab reinforcement belonging therewith; Fig. 4 another fragmentary side elevation of a reinforced column and floor slab, constructed in accordance with my invention, but of modified construction, the reinforcement also being shown by dotted lines; Fig. 5 a detail thereof, being a cross section 30 of Fig. 4 taken on the line 5-5; Fig. 6 a top or plan view of the column reinforcement and portions of the floor slab reinforcement belonging therewith; Fig. 7 still another fragmentary side elevation of a 35 reinforced column and floor slab, constructed in accordance with my invention, but of another modified construction, the reinforcement being likewise shown by dotted lines; Fig. 8 a detail being a cross section of Fig. 40 7 taken on the line 8-8; Fig. 9 a top, plan view of the column reinforcement, and of the floor slab reinforcement belonging therewith; Fig. 10 another fragmentary side elevation of a column and floor slab, constructed 45 in accordance with my invention, but of

modified construction, the reinforcement likewise shown by dotted lines; Fig. 11 a detail thereof, being a cross section of Fig. 10 taken on the line 11-11; Fig. 12 a top or plan view of the column reinforcement and of portions of the floor slab reinforcement belonging therewith; Figs. 13 and 14 top or plan views of the major part of the floor slab reinforcement.

Similar letters refer to similar parts 65 throughout the several views, A being the column, and B the floor slab.

In the practical application of my invention, I vary the construction somewhat, as the exigencies of the case may require, 70 adopting some one of the modifications herein shown and hereinafter described, or combinations of two or more of them; for example, when the column reinforcement consists of the banded and bound vertical rods *a*, as shown in Figs. 1, 2 and 3, I bend the said rods *a* outward at the top of the column A, and extend the laterally bent portions *a'* thereof horizontally, as shown in Fig. 3; but where the column reinforcement consists of the banded and bound bars *b*, of structural steel, as shown in Figs. 4, 5, 6, 7, 8 and 9 (bars too rigid to be practically bent) I employ the elbow ribs *c* shown in Figs. 4, 5, 6, 7, 8, 9 and 14, the vertical portions *c'* of which I arrange within the column A, and the horizontal portions *c''* of which I arrange within the floor slab B, as shown in Figs. 4 and 7, which elbow ribs thereby become parts of both the column 75 and the floor slab reinforcement.

Upon the horizontal portions *a'* of the vertical rods *a* constituting the column reinforcement shown in Figs. 1, 2 and 3, upon the horizontal portions *c''* of the elbow ribs 80 *c*, shown in Figs. 4, 5, 6, 7, 8, 9 and 13, or upon the band *d* at the top of the reinforcement of the column A, I arrange the carrying rings *e* shown in Figs. 3, 6 and 13, or the transverse bars *f* shown in Figs. 9 and 14. Upon these carrying rings *e* shown in Figs. 3, 6 and 13, or upon the transverse carrying bars *f* shown in Figs. 9, 12 and 14, I arrange the direct, transverse and diagonal rods *j* shown in Figs. 12, 13 and 14, 85 100 105 which rods constitute the major portion of my floor slab reinforcement.

A description in detail of each form of construction herein shown is as follows.

By reference to Figs. 1, 2 and 3 of the 110

drawing, it will be seen that the column reinforcement consists of a number of vertical rods *a* (usually eight) which rods are arranged in a circle, the diameter of which 5 is nearly as large as that of the column to be molded thereupon. These vertical rods (*a*) are united at intervals intermediate their length, by means of the bands *d*, said bands being secured to the vertical rods *a*; 10 by means of U-shaped bows or yokes *h*, which bows or yokes are secured thereto by means of the clamping nuts *i*. These vertical rods *a* I bend outwardly at the top of the column A, and arrange the laterally 15 bent portions *a'* thereof radially as shown in Fig. 3, which laterally bent portions extend into, and constitute a part of the floor slab reinforcement. Upon the radially arranged portions *a'* of the column reinforcement *a*, I place the carrying rings *e*, shown 20 in Figs. 3, 6 and 13, or the carrying bars *f*, shown in Figs. 7, 9, 12 and 14, upon which rings or bars in turn, I lay the direct, transverse and diagonal rods *j*, shown in Figs. 25 12, 13 and 14, which rods constitute the major portion of the floor slab reinforcement.

The width of each group or belt of rods *j* is at least the diameter or substantially 30 the diameter of the framework at the top of the column by which the group or belt is supported, and has such proportion to the distance from center to center of two nearest columns that the whole or substantially the whole of the slab is traversed by 35 reinforcing means so that the slab acts as a theoretical flat plate. Such proportion may be a width equal substantially or approximately to one half the distance from 40 center to center of two columns nearest each other, as illustrated in Fig. 13 of the drawings. With the belts of reinforcement extending from column to column in groups of four columns, the reinforcements lap 45 over each column in at least a four-fold layer, giving to the structure great stiffness and strength both in respect to the matter of supporting the slab under load and under lateral strains. Where the diagonal belts cross, there is a two-fold layer, and where the belts extend directly there is a single layer at midlength of the belt between two columns.

By reference to Figs. 4, 5 and 6 of the 55 drawing, it will be seen that the column reinforcement consists of a group or series of angle bars *k* (structural steel) which bars (like the vertical rods *a*) are united at intervals intermediate their length by 60 means of the transverse tie-plates *l*, which tie plates are arranged in two series, each alternate plate constituting one of the said series, and each alternate plate constituting the other one of the said series, the first 65 named series being arranged transversely

to the last named series. These plates (*l*) are secured to the vertical bars *k* by means of the rivets *n*, and the vertical bars *k* are bound at their upper ends by means of the band *d*. In this construction I employ the 70 elbow ribs *c*, arranging their vertical portions *c'* within the band *d*, and among the vertical bars *k*, which constitute the major part of the column reinforcement, and the horizontal portions *c*² of which I arrange 75 radially, as shown in Fig. 6. Upon the radially arranged portions *c*² of the elbow ribs *c*, I place carrying rings *e*, and on the latter I lay the direct, transverse and diagonal rods *j* shown in Figs. 12, 13 and 14, 80 which rods constitute the major part of the floor slab reinforcement.

By referring to Figs. 7, 8 and 9 of the drawing, it will be seen that, while the column reinforcement consists of vertical 85 bars of structural steel, the construction differs somewhat from the construction shown in Figs. 4, 5 and 6, inasmuch as the column reinforcement consists of three bars *o*, of structural steel, I-shaped in cross section, called usually I-beams. In this construction, (as in the construction shown in Figs. 4, 5 and 6) I employ elbow ribs *c* above described, and arrange thereupon the carrying rings *e*, shown in Figs. 3, 5 and 13, or 95 other equivalent carrying bars *f* shown in Figs. 9, 12 and 14. In this construction I perforate the upper portions of the vertical bars *o*, and pass one or more of the carrying bars *f* through the said vertical bars *o*, 100 as shown in Figs. 7 and 9, thereby binding a portion of the reinforcement of the floor slab B, to the reinforcement of the column A. In this construction the elbow ribs *c* may be dispensed with and the direct, transverse and diagonal reinforcing rods *j* be 105 laid directly upon the carrying bars *f*. This construction is practically adapted for use in the quarter round supports *p* at the corners of the room, and the half round 110 supports *q*, lying between them, which supports are adapted to receive the ends of the direct, transverse and diagonal rods *j* where the same abut the walls of a room or building.

By referring to Figs. 10, 11 and 12 of the drawing, it will be seen, that while the column reinforcement consists of banded and bound rods, it differs from the construction shown in Figs. 1, 2 and 3, inasmuch 115 as I do not bend the vertical rods constituting the column reinforcement horizontally, to constitute a part of the floor slab reinforcement, as in the first construction described. In this modification, I preferably employ eight vertical rods *r* arranged in the order shown in the two parallel series of three members each, and a pair of rods arranged between the said parallel series, all of the eight rods *r* being bound at their up- 120 125 130

per portions and at intervals intermediate their length by means of the bands *s*, and four of the rods *r* being similarly bound, by means of the bands *s'*, lying diagonally to the first-named band *s*. Upon the upper bands *s* and *s'*, I arrange the transverse rods or bars *f* shown in Figs. 12 and 14, upon which bars or rods I arrange the direct, transverse and diagonal rods *j* shown in Figs. 13 and 14.

Any or all of these forms relate to and properly belong to my invention, inasmuch as they have been suggested to my mind while in the capacity of an engineer I have been supervising the erection of structures of considerable magnitude in this and other countries.

By my construction, wherein a capital or enlargement is formed on the column, or in one piece therewith, and by the employment of my reinforcement, I am able to dispense with the use of beams on the under side of the floor slab. This is an immense advantage in every way. It is economical in the use of concrete; it is also economical in that it renders unnecessary the expensive forms for making the beams, and it means greater rapidity of work. As far as the finished structure is concerned, the absence of beams on the under side of the floor slab, enables partitions to be placed anywhere that it may be found desirable to place them. It results in better illumination from the windows, and there are no dirt-collecting corners, which exist where beams or girders are employed.

Another very important advantage resulting from the provision of a ceiling that is smooth, or free from beams or projections, is in the matter of fire protection. In fighting a fire with a stream of water from a hose, the obstruction offered by ribs or beams is obviously serious, since a rib may stop short a stream of water, whereas a flat smooth surface against which the stream is directed at an angle, will deflect and spread the water, causing it to descend to the floor over a wide area and to the best possible advantage. Where sprinkler heads are used in a ceiling, the cost of equipment by such a system of fire protection is substantially reduced, because fewer sprinkler heads are required with a flat or smooth ceiling than one where there are beams or ribs on the under side of the ceiling. In warehouses or similar buildings, my invention is of special value because in order to afford aisles or passageways, the load is naturally concentrated around the columns, and it is at these points, where the load therefore is greatest, that the greatest strength of the structure exists, by reason of the enlarged capitals of the columns, and their integral construction or formation with the slabs, and the heavy reinforcements of the structure immediately

at and adjacent to the column. The provision of the capitals on the columns by gradually increasing the diameter of the columns at the top, and making them and the slab an integral mass, takes care of the compression of the concrete which is the greatest over the columns.

As will be seen by reference to the drawings, the rods forming the framework or head at the top of the column extend laterally into the slab substantial distances beyond the sides of the column, and as the rods are anchored in or supported at their inner ends by the column structure, the arrangement is that of a cantaliver, so that I avail myself of a cantaliver for supporting the slab. The cantaliver action or effect may, however, be obtained otherwise than by stopping the anchored ends of the rods that form the cantaliver in or at the column. Thus rods could be extended on both sides of a column, and terminated at the desired points on both sides thereof; or across several columns, and projected at the free ends to the necessary points to get the cantaliver effect.

My aim in inventing my arrangement of reinforcement was to produce a flat plate floor that would act as nearly as possible like a continuous flat plate of homogeneous material supported directly by the columns without the intervention of and making unnecessary the costly and otherwise objectionable beams, the load being carried directly to the supports instead of around a corner, so to speak, as where beams are used. Reinforced concrete is not a homogeneous material, but a composite of two different materials—concrete and metal—possessing the marked differences or characteristics that the concrete like stone is suitable for compression but relatively weak and unreliable in tension, while steel is thoroughly reliable in tension. An analysis of the general character of the stresses involved, considering for simplicity a homogeneous plate, will make clear the character and the purpose and action of the reinforcement constructed and arranged to embody my invention. In the case of such a plate, and considering a section through the plate circular in form concentric with the column, and within the point of contraflexure, the effect of a uniform load upon the plate is to deflect it downward around the support or column. The stresses resulting are both radial in outward directions from the column, and circular along lines concentric with the column. In the composite plate of concrete and steel a simple plate of steel or other metal cannot be employed, but in its best or most practical form a substitute for a steel plate is afforded by my net-work arrangement of reinforcement which at the column has the form of a circumferential

cantaliver that takes care of these complex stresses and runs in multiple directions across the top of the column and into the slab and is situated in the tension zones in 5 the slab. Besides the unreliability of concrete in tension, it is unreliable in shear in its partially cured condition. This renders desirable the use of reinforcement near the columns or supports to take care of shear, 10 in addition to the belts of small rods that are employed for the slab reinforcement, and for this purpose I provide the framework of rods extending at the top of the column into the slab, and on said framework carrying 15 rods are arranged as a convenient means of holding the slab rods at the desired level in the slab. Of course, these additional rods add to the strength of the structure when it is thoroughly hardened.

20 Referring to the flat central plate, or the suspended slab portion, there is practically no bending moment at the center and the maximum stress occurs at one side of the center in a diagonal direction rather than the central portion. This distribution of stress greatly reduces the coefficient of bending and enables the use of a slab of less depth than is required in beam construction to secure economy.

25 30 By the expression "flat plate floor," used by me, is meant a column-supported slab requiring no exposed beams or girders projecting from it, but not necessarily flat in the strict or narrow sense, but one so reinforced as to have characteristics under load, 35 similar to those of the mathematical flat plate supported at points, or which acts substantially as a circumferential cantaliver about the column, in which the tensile reinforcement acts as the upper chord of the 40 cantaliver in resisting circular and radial stresses. Thus a floor slab in which there are depressions, or cut away portions in the under surface, or ceiling, at the central portion or other intermediate portions of the 45 panels, so that the slab is thinner at such central, or other intermediate portions, either for architectural effect, or to save material, if reinforced in accordance with 50 my invention, is such a floor as is contemplated by the expression "flat plate floor."

55 As this application possesses matter in common with an application filed by me January 23, 1905, Serial Number 242,431 it is to be treated as a continuation of said prior application as far as the common subject matter is concerned.

60 By the term "circumferential" appearing in the claims, I do not mean a form that is necessarily circular, but a form or shape, whether circular or polygonal, that has the characteristic of extending in every direction outwardly from the column axis. In the drawings I illustrate forms that are 65 angular as well as round, which it will be

seen by this explanation, are comprehended within the term "circumferential."

What I claim as new and desire to secure by Letters Patent is—

1. An arrangement of reinforcement for a column-supported flat plate floor of concrete, comprising a plurality of circumferential cantaliver members, respectively situated in the upper part of the slab at the columns and projecting therefrom, and reinforcing means extending from member to member in multiple directions through the space between said members, and filling, or substantially filling such space. 75
2. An arrangement of reinforcement for a column-supported flat plate floor of concrete, comprising a plurality of circumferential cantaliver frames, each composed of crossed rods situated in the upper part of the slab at the columns, respectively, and extending across and outward therefrom, and belts of rods extending from frame to frame in multiple directions, and filling or substantially filling the space between them. 85
3. An arrangement of reinforcement for a column-supported flat plate floor of concrete, comprising a plurality of open-work circumferential frames situated toward the top of the floor plate, and concentric with the columns, respectively, and extending 90 therefrom outward into the slab, and belts of slab reinforcements extending in multiple direction through the space between said frames, and covering the area therebetween. 95
4. An arrangement of reinforcement for a column-supported flat plate floor of concrete, comprising multiple belts of rods extending from column to column, and passing over the columns in the upper part of the floor, portions of said belts being beyond the columns on opposite sides and forming cantalivers, the cantaliver-forming portion of one belt forming a support for rods of another belt, the area between the columns being covered, or substantially covered by reinforcements. 100
5. An arrangement of reinforcement for a column-supported flat plate floor of concrete, comprising multiple belts of rods that extend from column to column in two directions directly, and in two directions diagonally, portions of said belts being beyond the columns on opposite sides and forming cantalivers, the rods running in intersecting directions crossing at the columns in 105 the upper part of the floor, and the cantaliver-forming portions of rods of one belt supporting rods of another belt, the area between the columns being covered, or substantially covered by reinforcements. 110
6. In an arrangement of reinforcement for a column-supported flat plate floor of concrete, the combination of vertical column-reinforcing bars, all of which terminate at 115 and are bent laterally into the floor slab, 120
- 125

- concentric rings upon the laterally bent portions of said rods, and belts of rods crossing said rings and extending in multiple directions between the columns.
- 5 7. In a structure of reinforced concrete comprising columns and flat plate floors, the combination of belts of rods extending from column to column having cantaliver ends projecting beyond the columns in two directions, of supplemental diagonal belts of rods of sufficient widths to substantially cover the remaining area between the columns and supported by the first named belts, said rods being toward the top of the slab at the 10 columns and toward the bottom of the slab between the columns, substantially as described.
8. In a reinforced concrete structure, consisting of floors of concrete supported by 20 columns, the combination of a circumferential cantaliver frame at the top of the columns, consisting of crossed rods, belts of rods extending from frame to frame, a belt being substantially the width of the frame, 25 said belts substantially covering the area between columns, and said belts of rods being nearer the bottom of the slab between supports, and the cantaliver frame being nearer the top of the slab.
- 30 9. In a reinforced concrete structure consisting of flat floor slab supported by columns, the combination of a head of wide-spreading reinforcement at the top of the column, consisting of elbow rods anchored 35 in the column, carrying rods supported on the elbow rods, and supplemental slab reinforcement supported thereby and radiating into the slab in every direction.
10. In a structure of reinforced concrete 40 comprising columns, and a flat plate floor slab, the combination of an open frame consisting of crossed rods at the top of a column extending partially into the slab contiguous to the column, and belts of rods extending 45 cross-wise of said open frame and passing through the slab directly and diagonally in straight lines from column to column.
11. The combination of concrete columns, and a flat plate floor slab of concrete supported directly thereon, horizontally arranged bars in the slab at the top of the 50 columns, and supported thereby with their free ends extending outward into the slab from the columns forming cantalivers, and 55 belts of reinforcement extending in multiple directions through the slab from support to support, and supported by said cantalivers.
12. In a monolithic concrete structure, the 60 combination of a concrete slab having a smooth ceiling or under surface, columns of concrete having capitals integral with the columns and integral with the slab, and directly supporting the slab, reinforcing bars extending vertically through the 65 columns, and horizontally from the upper ends thereof into the slab at the head of the columns, and horizontally extending bars in the slab supported on the column reinforcing bars.
13. In a monolithic concrete structure, the 70 combination of a concrete slab having a smooth ceiling or under surface, columns of concrete having capitals integral with the columns and integral with the slab, and directly supporting the slab, reinforcing 75 bars extending vertically through the columns, and horizontally from the upper ends thereof into the slab at the head of the columns, and horizontally extending bars in the slab supported on the column reinforcing bars.
14. In a monolithic concrete structure, the 80 combination of a concrete slab having a smooth ceiling or under surface, columns of concrete, reinforcing bars extending vertically through the columns, and horizontally from the upper ends thereof into the slab, and horizontally extending bars in the slab supported by the column-reinforcing bars.
15. The combination of columns of concrete, and a flat plate floor slab of concrete supported directly thereon, belts of reinforcement extending between the columns, the width of each belt being substantially 90 the same as one half the distance between 95 two columns that are nearest each other, and an open framework at the tops of the columns supporting said belts of reinforcement and having a width substantially the same as the width of a belt.
16. The combination of concrete columns, and a flat plate floor slab of concrete supported directly thereon, horizontally arranged open frames embedded in the concrete at the top of the columns extending 105 transversely of the column axis, belts of reinforcement extending in multiple directions through the slab from column to column and supported by said frame, the belts being of a width to substantially cover the 110 area between the columns.
17. In a reinforced concrete structure, the combination of supports, consisting of columns of concrete, and a flat plate floor slab of concrete supported directly thereon, belts 115 of reinforcement extending through the slab to the supports in four directions, said reinforcements having a thickness of four belts over the support in the upper part of the slab, a thickness of two belts in a diagonal direction midway between the supports in the bottom part of the slab, a thickness of one belt midway between the supports directly from one support to the other in the lower part of the slab, and a set of reinforcements extending transversely of the 120 column axis and projecting beyond the tops of the columns.
- 125

18. In a steel skeleton concrete construction, the combination of a vertically reinforced column and a floor supported thereby, the vertical reinforcing bars of the said 5 column being bent laterally outward and extended radially into said floor, carrying bars resting upon and supported by the horizontal portions of said laterally bent bars, and horizontal bars in said floor arranged upon said carrying bars, said reinforcing bars extending directly from column to column substantially as shown and described.

19. In steel skeleton concrete construction, the combination of a vertically reinforced column the column reinforcement consisting of vertically extending bars, and a floor slab supported thereby, said column reinforcing bars being bent laterally and 10 extending into the said floor slab, carrying bars arranged upon the laterally bent portion of said column reinforcement, and floor slab reinforcing bars arranged upon the said carrying bars and extending directly 25 and diagonally from column to column as shown.

20. In a reinforced concrete construction, the combination of a floor slab and a vertically reinforced column having vertical reinforcing bars bent laterally into the floor slab, carrying bars arranged and supported on the laterally bent portions of said bars, and direct and diagonal reinforcement in the slabs running from column to column.

21. The combination of a concrete floor slab, and a vertically reinforced column having vertical reinforcing bars bent laterally into the floor slab, carrying bars arranged and supported on the laterally bent 35 portions of said bars, and direct and diagonal reinforcement in the slabs running from column to column.

40

nal reinforcement in the slabs running from column to column.

22. The combination of a vertically reinforced concrete column, and a concrete floor supported thereby, the vertical reinforcing bars of the said column being bent laterally outward and extended radially into the said slab, carrying bars resting upon and supported by the horizontal portions of the said laterally bent bars, and horizontal bars 50 in the said floor arranged upon the said carrying bars, said reinforcing bars extending directly from column to column, substantially as shown and described.

23. The combination of concrete columns, 55 a concrete floor supported thereby, having a smooth ceiling or under surface, vertically extending reinforcing members in the columns, reinforcing members that extend in a circular series concentric with the columns 60 and into the floor at the top of the column, and horizontally extending reinforcing members in the floor supported by said circular series of reinforcing members, and extending therefrom into the floor.

24. The combination of a concrete column comprising a series of vertical bars, means connecting said bars and forming a framework therewith, a framework at the top of the column extending laterally outward in 70 different directions, and consisting of a series of radial members and concentric circular members supported by the radial members, and a concrete slab supported by the column and integral with the column.
